UNITED STATES PATENT OFFICE

FRED ATTENBOROUGH, OF HARRINGTON PARK, LONG EATON, ENGLAND

CIRCULAR KNITTING MACHINE

Application filed April 10, 1928, Serial No. 268,980, and in Great Britain October 3, 1927.

This invention comprises improvements in or relating to circular knitting machines and has for its principal object to provide means whereby a practically unlimited range or variation of patterns can be produced in fabrics and articles knitted on such machines.

The type of machine to which this invention refers is that embodying a series of displaceable thread guides, a rotary cam device 10 operating to displace the guides to lay threads on the machine needles, and jacquard mechanism for effecting a variable selection of the guides to be operated by said cam, and it is a further object of this invention to provide 15 means in connection with such a machine for producing an all-round pattern, i. e. a pattern extending around the whole circumference or at any position in the circumference of the fabric.

With the above objects in view, a feature of the present invention consists in the provision in a machine of the type referred to of means whereby a variable selection of the thread guides to be operated by a rotary cam 25 device is effected by the displacement by jacquard mechanism of separate elements which function intermediate of the cam and guides.

By effecting the selection of guides by the operation of the separate intermediate elements as above the guides can be mounted to 30 operate in the customary manner without the necessity of transmitting to said guides any movement other than the usual lateral movement across the needles.

Another feature of the invention consists 35 in the provision of means for positively operating the members disposed intermediate of the cam and guides so as to permit the return to the neutral or inoperative position of displaced thread guides prior to each selection thereof.

More particularly the invention consists in the provision of a circular knitting machine comprising in combination, a circular row 45 of radially displaceable depending thread guides, a rotary cam operating to displace said guides from a non-feeding to a feeding position or vice versa through the medium of a series of separate vertically displaceable 50 jacks, jacquard mechanism operating to move

selected jacks from an inoperative to an operative position between the guides and cam so as to determine the selection of guides, and means for returning the displaced jacks to a neutral or inoperative position prior to each 55 operation thereon by said jacquard mechanism.

For the purpose of more fully describing the nature of this invention reference will now be made to the accompanying drawings, 60 wherein:—

Figure 1 is a vertical section through a part of a circular knitting machine in accordance with this invention.

Figure 2 is a part-sectional elevational 65 view of part of the machine shown in Figure 1 looking in the direction of arrow X.

Figure 3 is an enlarged elevational view of the jacquard mechanism.

Figure 4 illustrates the jacquard mechanism and a method of operating the same. 70

Figure 5 is a detail view showing the cam from which the jacquard mechanism is controlled.

Figure 6 is a detail plan view illustrative of 75 the jacks 38 and the manner in which they operate to move the thread guides laterally so as to cause the guides to wrap the threads about the needles.

In the method of carrying out the invention illustrated in the drawings, to an outstanding ring or flange 1 suitably secured to a stationary sleeve member 2 are mounted depending thread guides 3 arranged in a circular row, the lower or feeding ends of the 80 guides being disposed approximately level with the hooks of needles 4 when the latter are raised to take thread. The guides 3 are suspended in the known manner by their hooked ends 3a so as to be capable of a radial oscillatory movement for moving the lower ends from an inoperative position inside the needles to a feeding position exterior to said needles, the springy nature of the guides effecting the opposite movement thereof and normally maintaining same within the 85 needle row.

On a rotatable tubular spindle 5 which turns within the sleeve 2 about a central fixed spindle 5a is secured a cam 6 preferably com- 100

prising a flanged collar with circumferential projection or cam bit, and located between said cam and the guides is a series of vertically movable jacks 7 formed with enlargements or butts 7a which, when the jacks are moved to bring same in horizontal alignment with the cam 6, function to effect outward radial movement of the guides each time the projection on said cam comes into engagement therewith.

A depending guide may be provided for each needle, or one guide may serve two or more needles, and the number of jacks coincides with that of the guides. The guides 15 are formed with outwardly bent portions 3b or otherwise suitably shaped so that when the jacks 7 are moved down, the butts 7a coincide with said bent parts 3b and the rotation of the cam 6 has no effect on the guides.

20 The jacks 7 are guided in their vertical movement by causing upwardly extending parts 7b thereof to pass through perforations in the fixed flange 1, and to effect the lifting to the operative position of selected jacks at 25 predetermined intervals, jacquard mechanism is provided located above the machine.

Preferably two jacquard devices are provided, one appertaining to the jacks around one half of the machine and the second appertaining to the jacks in the other half.

30 Each jacquard device comprises one or more series or rows of closely disposed pins 9 slidable within perforated guide bars 10 extending between side plates 11, one pin being provided for each jack 7 and being connected thereto by cords or wires 12 attached to the upper ends of the jack extensions 7b and to bent parts 9a of the pins.

35 The sliding pins 9 coact at one end with an intermittently rotatable member 13 of hexagonal or other polygonal shape over which passes an endless chain of jacquard cards 14 which are retained upon the rotating member 13 by any desired means, the several cards 40 being perforated in the well known manner.

45 Each jacquard device is conveniently operated from a cam 15 on any suitable drive shaft 16 of the machine. With this cam, which is advantageously a groove, two cam trucks or rollers 17 engage, one appertaining to each jacquard, and disposed at diametrically opposite positions in said groove. Each cam truck 17 is rotatably carried between the 50 ends of a lever 18 which is pivoted at its one end to the machine frame at 19 and jointed at its other end to the lower extremity of a vertically extending rod 20, which rod at its upper end is adjustably connected to a centrally pivoted lever 21.

60 Each lever 21 is connected preferably by fork and pin connection, to a longitudinally slidable rod 22 guided in sleeves 23 on one of the side plates 11 of the jacquard mechanism, and each of said slidable rods 22 is

suitably connected to one of the aforesaid polygonal jacquard card carriers 13.

65 Freely pivoted on each pivot 21a of the levers 21 is a clawker arm 24 which engages with pins 25 projecting from an end plate or star wheel 26 fixed at one end of each jacquard carrier 13 to rotate with said carrier, said clawker functioning to effect intermittent rotation of said carrier. A spring 27 assembled between a fixed disc 28 and a slidable disc 29 serves to press the latter on to the wheel 26 so as to retain the carrier 13 from rotation beyond the required extent at 75 each motion.

80 The operation is such that at each revolution of the cam 15 the two cam trucks 17 ride successively over the cam rise 15a so as to lift first one lever 18 and then the other. The upward movement of a lever 18 transmits through rod 20 a pivotal movement of lever 21 and in so doing displaces the sliding rod 22 to move the carrier 13 with the cards out of engagement with the pins 9 and through the clawker 24 partially rotate the carrier to bring a new card into position for engagement by said pins. Immediately the cam truck 17 has passed the rise 15a the operation is reversed and the fresh card moved up to the pins 9, and in so doing certain of said pins registering with the perforations in the card will pass through same and remain stationary while the remaining pins will coact with the unperforated part of the card and be 90 slidably displaced.

95 This movement of selected pins 9 effects 100 through the aforesaid cords 12 an upward movement of the jacks 7 connected thereto to bring the butts 7a thereon level with the rotary cam 6, the remaining jacks connected with the unmoved pins 9 being retained down 105 in the inoperative position, and in this way only those guides 3 which are opposite to the raised jacks are moved out for laying thread upon the needles.

110 As before stated, each jacquard governs 110 the selective operation of jacks and consequently also the guides of one half of the circumference of the machine, and as the jacquards operate alternately, the jacks are selectively displaced in one half while the 115 cam projection on the rotary cam 6 is traversing the opposite half.

120 During the time a cam truck 17 is riding over the cam rise 15a and the jacquard carrier 13 of one jacquard device is moved away 120 from the pins 9 appertaining thereto, that is to say, immediately prior to each motion of the jacquard for effecting selection of the jacks, it is necessary that said pins and the series of jacks 7 governed thereby are returned to the neutral or inoperative position. In the present invention this is positively accomplished by providing a flanged ring 30 formed in two independently movable halves and assembled in a vertically slidable manner 130

around the sleeve part 2 or member encircling same at a position above inwardly projecting butts 7c on the jacks 7. Each half ring section 30 is carried by a pair of bolts or pins 31 extending up through and slidable within holes in the guide carrier ring 1 and an outstanding flange or portion of the stationary sleeve 2, the upper ends of said bolts 31 having secured thereto a flat plate 32 having on its upper face a suitably shaped and positioned cam rise 33.

Normally each ring section 30 is held up immediately beneath the guide carrier ring 1 by springs 34 as represented at the left side of Fig. 1. When, however, one of the cam trucks 17 is located on the cam rise 15a and a jacquard carrier displaced from its coacting pins 9, a projecting roller 35 or equivalent member carried by a boss 36 rotating with the tubular spindle 5 coacts with and rides up the cam rise 33 and in so doing depresses one of the ring sections 30 which by engagement with the butts 7c of jacks 7 depresses all raised jacks into a neutral position ready for a further selection on the next motion of the jacquard, Fig. 2 and the right side of Fig. 1.

At the time the cam 6 operates on the selected guides to move same radially outwards, a further cam installed within a rotatable part 37 fixed to the lower end of the rotary tubular spindle 5 coacts with radially displaceable jacks 38 accommodated within tricks in a relatively fixed carrier 39 to push same outwards and press the operative guides laterally so as to traverse the needles, it being understood that the guides 3 return to the non-feeding position by their own spring action when the cam 6 has travelled past same and the radial jacks 38 have been withdrawn.

As will be noted in Fig. 1 the jacks 38 are positioned well above the needles 4. These jacks are cranked as shown and are sequentially moved outwardly as the thread guides 3 have been moved to the front of the needles, as represented in Figure 6. The bent or cranked portion of each jack by reason of its engagement with the needle guide with which it cooperates, moves the guide laterally across and in front of the needle as the guide is projected, as indicated by dotted lines in Figure 6. The guide so moved, upon being released from the action of the cam 6 returns to the rear of the needle under its own spring action, and the jack 38 is then drawn to normal position within the carrier 39 and allows the guide to move back to normal position across the back of the needle. Thus the thread is completely wrapped around the needle.

The requisite rotation is transmitted to the tubular spindle 5 from a drive shaft 40 through bevel gears 41 within a gear case 42 fixed to the machine frame.

By employing a machine as above described for knitting stockings and socks, a pattern of a continually varying nature can be pro-

duced along the entire length and/or circumference of the article, and it will be appreciated that the changing from one pattern or range of patterns to another is readily effected by the simple operation of changing the jacquard cards.

I claim:

1. In a circular knitting machine, a series of radially displaceable depending thread guides arranged in a circular series, a rotary cam device operating within the circle of thread guides to displace said guides to lay threads on the machine needles, separate vertically displaceable jacks located between the cam and guides, jacquard mechanism functioning selectively to raise said jacks from an inoperative position to a position wherein same act upon and select the guides to be radially displaced by the cam and positive means for lowering the jacks to the inoperative position after having been raised by said jacquard.

2. In a circular knitting machine, a series of radially displaceable depending thread guides, a rotary cam device, a series of separate vertically displaceable jacks functioning intermediate of the guides and cam to effect displacement of the guides for feeding thread to the machine needles, a plurality of jacquard mechanisms, means for successively operating said jacquard mechanisms, each jacquard mechanism being connected to and functioning selectively to displace a separate series or group of jacks appertaining to a separate series or group of guides so as to enable selected guides to be radially displaced by the rotary cam, and means whereby the displaced jacks are returned to their normal position after displacement.

3. In a circular knitting machine, a circular row of radially displaceable depending thread guides, a rotary cam operating within said circle of guides, a circular row of vertically displaceable jacks located between said cam and guides, a plurality of jacquard mechanisms operating to raise selected jacks from an inoperative position to a position wherein same function to transmit outward radial movement from the rotary cam to guides selected by said jacks, each jacquard mechanism operating upon a group of jacks forming a section only of the complete circular row of jacks, a cam device, functioning to operate the jacquards in succession, and means for lowering the raised jacks to a neutral position prior to each operation thereon by its associated jacquard mechanism and during the time the jacks of the other group are being selected.

4. In a circular knitting machine, a circular row of radially displaceable depending thread guides, a rotary cam operating within said row of guides, a circular row of vertically displaceable jacks located between said cam and guides, a plurality of jacquard

mechanisms operating to raise selected jacks from an inoperative position to a position wherein the same function to transmit outward radial movement from the rotary cam to guides selected by said jacks, each jacquard mechanism operating upon a group of jacks forming a section only of the complete circular row of jacks, means functioning to operate the jacquards in succession, butts on said 5 jacks, a vertically slidable ring formed in a plurality of part-circular sections, each ring section being associated with an independent group of jacks and coacting with the butts of said jacks, upstanding vertically movable members connected to said ring sections, cam pieces carried by said upstanding members, a rotary member functioning during rotation to coact with said cam pieces in succession and successively depress each ring section 10 so as to lower to an inoperative position jacks previously raised by the jacquards, and spring means operating to lift the ring sections after each depression thereof, and means for moving across the needles those 15 guides which are radially displaced by the 20 rotary cam.

5. In a circular knitting machine, the combination of a circular row of radially displaceable thread guides, a rotary cam for 25 successively operating said guides, a circular row of displaceable jacks arranged between the said cam and the thread guides, a plurality of operating jacquard mechanisms respectively connected with and operating segmental groups of the jacks to move selected 30 jacks from inoperative to operative position where they function to transfer motion to the needle guides from the rotary cam and means to restore the jacks to normal inoperative position prior to each operation thereon by jacquard mechanism.

6. In a circular knitting machine, a series 40 of radially displaceable depending thread guides, a rotary cam device movable within the circle of the thread guides, a series of 45 separate vertically displaceable jacks functioning between the thread guides and the rotary cam device to effect radial displacement of the guides for feeding threads to the 50 machine needles, a plurality of jacquard mechanisms each operating in connection with a group of displaceable jacks, means for successively operating the jacquard mechanisms for selectively displacing the jacks of the group with which it is associated to bring the selected jacks into position to be acted upon by the cam device, to cause the radial displacement of the selected thread guides, and means for positively moving all the displaced 55 jacks of a series into neutral or inoperative position during the time the jacks of another group are being selected by the jacquard mechanism for that group.

7. In a circular knitting machine, a series 60 of displaceable thread guides, a rotary cam

device operating to displace said thread guides radially of the needle circle to lay threads on the said needles, separate displaceable elements interposed between said cam and guides and arranged to be moved 70 radially by the said cam and to impart the said radial movements to the thread guides, and jacquard mechanism operating selectively to displace said intermediate elements vertically and by so doing variably select the 75 thread guides to be operated by the cam device.

8. In a circular knitting machine, a series 80 of depending thread guides, a rotary cam device operating to displace said thread guides radially of the needle circle to lay threads on the said needles, separate jacks displaceable vertically independently of the thread guides, interposed between said thread guides and their operating cam, said jacks being arranged to be moved radially by the said cam and to impart the radial movements to the guides, jacquard mechanism functioning selectively to raise said jacks from an inoperative 85 position to a position wherein same act upon and select the guides to be radially displaced by the cam and positive means for lowering the jacks to the inoperative position after having been raised by said jacquard.

9. In a circular knitting machine, a series 90 of depending thread guides, a rotary cam device operating to displace said thread guides radially of the needle circle to lay threads on the said needles, separate jacks displaceable vertically independently of the thread guides 100 interposed between said thread guides and their operating cam, said jacks being arranged to be moved radially by the said cam and to impart the radial movements to the guides, a plurality of jacquard devices, 105 means for successively operating said jacquards, each jacquard being connected to and functioning selectively to displace needles of a series or group of guides so as to enable selected guides to be radially displaced by the 110 rotary cam, and means whereby the displaced jacks of a group are returned to their normal position after displacement and while the jacks of another group are being selected.

10. In a circular knitting machine, a series 115 of depending thread guides, a rotary cam device operating to displace said thread guides radially of the needle circle to lay threads on the said needles, separate jacks displaceable vertically independently of the thread guides 120 interposed between said thread guides and their operating cam, said jacks being arranged to be moved radially by the said cam and to impart the radial movements to the guides, a plurality of jacquard devices, means 125 for successively operating said jacquards, each jacquard being connected to and functioning selectively to displace selected jacks of a separate series or group of jacks appertaining to a separate series or group of guides 130

so as to enable selected guides to be radially displaced by the rotary cam, and independently operable means provided in connection with each separably operable series or group of jacks for positively and simultaneously moving all displaced jacks of said series into a neutral or inoperative position prior to each operation by the jacquard.

11. In a circular knitting machine, a circular row of radially displaceable depending thread guides, a rotary cam operating within said row of guides, a circular row of vertically displaceable jacks located between said cam and guides and arranged to be displaced radially to impart the radial displacement to the guides, a plurality of jacquard devices operating to raise selected jacks from an inoperative position to a position wherein the same function to transmit outward radial movements from the rotary cam to guides selected by said jacks, each jacquard operating upon a group of jacks forming a section only of the complete circular row of jacks, a cam device, functioning to operate the jacquards in succession, and means for lowering the raised jacks to a neutral position prior to each operation thereon by the jacquards.

12. In a circular knitting machine, a circular row of radially displaceable depending thread guides, a rotary cam operating within said row of guides, a circular row of vertically displaceable jacks located between said cam and guides and arranged to be displaced radially to impart the radial displacement to the guides, a plurality of jacquard devices operating to raise selected jacks from an inoperative position to a position wherein the same function to transmit outward radial movements from the rotary cam to guides selected by said jacks, each jacquard operating upon a group of jacks forming a section only of the complete circular row of jacks, means functioning to operate the jacquards in succession, butts carried by said jacks, a vertically slideable ring formed in a plurality of part-circular sections, each ring section being associated with an independent group of jacks and coacting with the butts of said jacks, upstanding vertically movable members connected to said ring sections, cam pieces carried by said upstanding members, a rotary member functioning during rotation to coact with said cam pieces in succession and successively depress each ring section so as to lower to an inoperative position jacks previously raised by the jacquards, and spring means operating to lift the ring sections after each depression thereof, and means for moving across the needles those guides which are radially displaced by the rotary cam.

FRED ATTENBOROUGH.
